J.C. Clayton & Co.

United States Patent Office.

S. E. ADAMSON, OF PHILADELPHIA, PENNSYLVANIA.

Letters Patent No. 98,327, dated December 28, 1869.

IMPROVEMENT IN CARD-HOLDERS.

The Schedule referred to in these Letters Patent and making part of the same.

To all whom it may concern:

Be it known that I, S. E. ADAMSON, of Philadelphia, in the county of Philadelphia, and in the State of Pennsylvania, have invented a certain new and useful "Improvement in a Combined Sign and Draw-Handle;" and I do hereby declare that the following is a full, clear, and exact description thereof, reference being had to the accompanying drawings, and to the letters of reference marked thereon, in which—

Figure 1 is a front view of the pull and sign attached to the drawer and ready for use.

Figure 2 is a back view of the pull or handle, detached from the drawer, and showing the manner in which the sign is secured to the pull.

Figure 3 is a transverse sectional view, showing the groove in which the sign is placed, and the spring by which the sign is held in place.

The nature of my invention consists in the adjustable spring in combination with the groove, draw-pull, and sign, attached to a drawer, as more fully herein-after described.

To enable others skilled in the art to make and use my invention, I will proceed to describe its construction and operation.

A is the face of the drawer;

B, the pull or handle; and

C, the sign.

In constructing the pull or handle, I use cast-metal, and may cast the same of any ornamental style desired, but always casting it with a concaved projection in front, so as to leave room for the fingers to enter to pull the drawer out with, and also with an open frame above the pull, and as long as it, with the opening about an inch or more wide, through which the sign is to be seen, all in the usual way. On the back of the pull it is flat, so as to lay smoothly against the face of the drawer.

A groove, D, is cast, say, half an inch wide, more

or less, around the opening, into which the sign is let.

At one end of the frame the groove D extends entirely to the edge of the pull, and at this end is secured a spring, E, (see figs. 2 and 3,) extending across the groove D, so as to keep the sign C from working out while pulling the drawer.

The flat under surface of the pull is shown in figs. 2 and 3.

a a are screws for attaching the pull to the drawer.

The sign is to be printed on suitable strips of pasteboard, or other stiff paper.

The strip on which the sign is printed is cut so as to fit into the groove D, and set into the same, (groove D,) and under the spring E, keeping it in proper position, as shown in figs. 2 and 3.

By turning the spring E outward, as shown by dotted lines at e in fig. 2, the sign can be shoved in the groove D of the frame, while the pull is screwed on the drawer, or can be removed in the same manner without loosening the screws a a.

If at any time I wish to change the sign, I have simply to turn out the spring, and shove the sign out that is under it, and insert a new one in its place in the manner as before described.

Having thus fully described my invention,

What I claim as new, and desire to secure by Letters Patent, is—

The adjustable end spring E, in groove or slot D, in combination with the pull B and sign or label C, constructed substantially as described, and operating as and for the purposes set forth.

In testimony that I claim the above-described improvement, I have hereunto signed my name, this 13th day of September, 1869.
